United States Patent

Des. 235,906

Patented July 15, 1975

235,906

AERIAL TOY

Abel Napodano, Berlin Center, Ohio
(4093 Columbiana Road, New Springfield, Ohio 44443)

Filed Dec. 10, 1973, Ser. No. 423,512

Term of patent 14 years

Int. Cl. D21—01

U.S. Cl. D34—15 HS

FIG. 1

FIG. 2

FIG. 3

FIG. 4

FIG. 1 is a top plan view of an aerial toy showing my new design;

FIG. 2 is a side elevational view thereof;

FIG. 3 is a bottom plan view thereof; and

FIG. 4 is a cross sectional view of FIG. 1 taken on line 4—4.

I claim:

The ornamental design for an aerial toy, as shown.
